UNITED STATES PATENT OFFICE.

FRANZ RAUCHWETTER, DECEASED, LATE OF BERLIN-FRIEDENAU, GERMANY; BY
ALFRED FLATER, ADMINISTRATOR, OF BERLIN, GERMANY.

CLEARING-SIGN HAMMER MECHANISM.

Application filed December 14, 1922. Serial No. 606,986.

To all whom it may concern:

Be it known that FRANZ RAUCHWETTER, late a citizen of the German Republic, and a resident of Berlin-Friedenau, Germany, 5 has invented certain new and useful Improvements in and Relating to Clearing-Sign Hammer Mechanisms, of which the following is a specification.

In case of calculating machines having a 10 printing mechanism it is necessary to separate the various calculations following each other. For this purpose a so-called "clearing-sign" is used printed with the first item of a new calculation and when being printed 15 indicates that the preceding calculation is completely finished, in other words, that the machine is clear and ready for a new calculation. As a complete calculation finishes with a total sum which is printed, it 20 has also already been proposed to so set the hammer which, when beginning a new calculation, is supposed to strike against the adjusted type rod of the clearing sign, that its actuating mechanism is set in advance 25 when printing the total sum of the preceding calculation and is released when printing the first item of a new calculation. To this class of hammer mechanisms for the printing of the clearing sign also belongs the 30 invention which forms the subject matter of this application.

The object of the present invention is to provide improved means whereby the releasing mechanism of the clearing sign hammer 35 may be put into or out of operation automatically as may be required during the operation of the calculating machine.

In the accompanying drawings which show an embodiment of my invention.

40 Figure 1 is a side elevation of the hammer actuating mechanism for the clearing sign in a position corresponding to the printing of the first item of a new calculation.

45 Figure 1^a is a similar view of the same in a position corresponding to the commencement of the total printing.

Figure 2 is a side elevation of the same in a position corresponding to the printing of 50 the current item or to the intermediate printing.

Figure 2^a is a perspective view of the same, in the same position, and in connection with the moving devices for the counting mechanism.

Figure 3 is a front elevation of the same.

Figure 4 is a detailed perspective of the lever 124 forming a part of the mechanism for actuating the coupling lever.

As such may be seen from the drawing, 1 60 is the type rod for the sign with the clearing sign type 3 which by means of the lever 2 is set by the keys. After the setting has been effected, the clearing sign 3 is within the path of the clearing sign hammer 51. 65 In this position the pin 61' of the type rod 1 holds down a lever 85 below the swinging path of a lever 59 fixed to arms 58 which are mounted on the swinging shaft 55. If the lever 85 were lifted so that its notch 90 70 is in the path of the lever 59, upon a swinging of the lever 59 to the left, the lever 85 would be forced to follow the movement and thereby the catch lever 54 of the hammer 51 75 swinging about the pin 54' is disengaged 80 from said hammer so that the latter is released and can be made to strike by the action of its spring 53. For the type rods of the numerals following the type rods 1 for the clearing marks to the left and corresponding to the separate number columns of the calculating machine a plurality of such hammer actuating mechanisms for the signs 85 are arranged side by side which upon the setting of a number in the above described 85 manner are moved by the lever 59 as is usual in machines of this class, only one such mechanism being here shown in the drawings. These hammer actuating mechanisms for the numbers with the disengaging levers 90 85 must now in case of calculating machines be consecutively coupled to each other so that the mechanisms following a set of mechanisms to the right are continuously released for the printing of the zeros. This 95 can be effected by means of special auxiliary levers mounted on the disengaging levers 85 for the hammers for the numerals which are in the path of stop or pins on the disengaging levers 85 following on 100 the left. The hammer mechanisms for the type rod 1 for the sign however must not be forced to follow the movement of the rod following the mechanism for the unit place hammer on the left, as in such a case, upon 105 a consecutive printing of the items or intermediary sums, the clearing sign would also be printed. In accordance with this invention means are provided to prevent the clearing sign from being printed until a 110

complete calculation is finished, and immediately prior to the printing of the first item of a new calculation. This is achieved by means of a special coupling lever 117 hinged to the lever 85 of the hammer mechanism for the sign, which swings about a journal 86 of the lever 85 and in a certain position is moved by a pin 84 of the lever 85 of the hammer mechanism for the unit 10 places following on the left. This position in which the coupling lever 117 is forced to follow the movement of the pin 84 of the lever 85 of the hammer mechanism for the unit on the left and thus also carries along 15 the disengaging lever of the hammer mechanism for the sign on which it is mounted, is shown in Fig. 1, or in Fig. 1^a in dotted lines respectively, while in Fig. 2 and Fig. 2^a (or in Fig. 1^a in full lines) those positions 20 of the coupling lever 117 are shown in which it is not affected by the pin 84 of the lever 85 of the hammer mechanism for the unit places following on the left so that therefore in this position a disengaging of 25 the hammer mechanism for the sign does not take place, a position, corresponding to the current printing of the items and intermediary sums.

For moving the coupling lever 117 from the end position Fig. 1 for the clearing sign printing into the end-position Fig. 2 for the current printing of items or intermediary sums, the clearing mark hammer 51 swinging about the journal 52 has been provided with a projection which upon a shooting forward of the clearing sign hammer 51 into the printing position strikes against the extension 118 of the coupling lever 117 thereby forcing it back into the position shewn in Fig. 2 and Fig. 2^a. The coupling lever 117 is in this case held by friction to the journal of the disengaging lever 85 so that it remains in the position into which it has been brought in every case (position Fig. 1 or Fig. 2). The right end of the coupling lever 117 is provided at one end at the lower side with a flange 121 and at the upper side with a flange 120 which are spaced apart a distance greater than the 50 width of the lever 85 and extend into the path of movement of said lever and are arranged respectively below and above the same. The edge 122 of the flange 120 is set back to a slight extent with regard to the edge of the flange 121 so that in the position of the coupling lever 117 shewn in Fig. 2, the pin 84 of the hammer mechanism for the unit places following on the left when moving does not strike against the back 55 edge 122 and in consequence also cannot actuate the coupling lever 117 and disengaging lever 85 of the hammer mechanism for the sign which must not take place with a current printing of items and intermediary sums. If however the coupling lever

117 assumes the position shewn in Fig. 1, the edge of the limiting flange 121 enters the path of the pin 84 of the hammer mechanism for the unit places following on the left, so that now upon a moving of the hammer mechanism for the unit places the pin 84 thereof forces the coupling lever 117 and thus also the disengaging lever 85 of the hammer mechanism for the clearing sign to follow its movement and consequently the 70 hammer mechanism for the clearing sign is disengaged. The advance adjustment of the coupling lever 117 for the hammer mechanism of the clearing sign into the position shewn in Fig. 1 is effected in every instance 75 upon the moving of the counting mechanism for the printing of the total sums, while however upon the moving of the counting mechanism corresponding to the current printing of items or intermediary sums the 80 coupling lever 117 is not actuated, but remains in the position shown in Figs. 2 and 2^a. This is achieved by means of a special mechanism the movement of which depends on the one hand upon the movement of the 85 counting mechanism that is to say, the raising and lowering of the counting mechanism, and on the other hand upon the uniform movements of the machine crank. This mechanism consists of a lever 124 rotatable on a fixed axle 123, the lever being 90 shown in perspective in Fig. 4. By means of a spring 125 the lower arm of this lever provided with a curve 126 is constantly drawn to the left in such a manner that the 95 curve 126 is in the moving path of a pin 127 of a vertically movable swinging rod 75. If the pin 127 upon its downward movement strikes the curve 126, the lever 124 is turned about the axle 123 in such a manner 100 that its lower arm swings to the right and its upper arm to the left. Thus it produces a swinging according to the time of the movement of the rod 75 which in consequence of the bell crank lever 116 swinging about the journal 77 by means of the swinging rod from the machine crank or machine shaft is raised and lowered with every actuation of the machine crank (compare 105 in particular Figs. 1^a and 2^a). 110

To the upper end of the lever 124 a pin 128 is fastened which projects into a slot 129 of a guide 130. This guide 130 is hinged at its lower end, as at 131^a to a double lever 132 swinging about a fixed axle 131. The double lever 132 is arranged to be swung out by a crank 133 mounted on a shaft 133' rotated by the lifting disc for the counting mechanism. For this purpose on the shaft 133' a crank 133'' is mounted hinged to the rod 10 of the 115 counting mechanism supported on the lifting disc so that the crank 133 is swung out according to the raising and lowering of the rod 10 of the counting mechanism and consequently also according to the moving of the 120 rod 10. 125

lifting disc 4' for the counting mechanism. The moving of the lifting disc 4' for the counting mechanism is effected by means of swinging rods 8 and 9 which are provided with angular slots 6 and 7 through which passes a pin 5, said rods being actuated from the machine crank in various phases according to whether counting mechanism for the consecutive printing of the items, of the intermediate sums or of the total sums must be raised or lowered. The rails 22 and 22' and levers 21 and 21' serve for the corresponding adjustment of the push rods 8 and 9 for the printing of the intermediate sums or of the total sums respectively by the rod 22 being connected to the key corresponding to the fixed figure of the intermediate sum and the rod 22' to the key corresponding to the fixed figure of the total sum. The result of this is that the double lever 132 swings up and down according to the stroke of the counting mechanism and imparts an up and down movement to the guide 130 which by means of the pin 128 engages with the slot 129 of the lever 124 so that with every up-movement of the counting mechanism the guide is pushed upwards.

Figs. 1 and 1^a correspond to the lowered position of the counting mechanism, Figs. 2 and 2^a to the raised position thereof. On the upper end of the guide 130 the element 135 turns freely on the pin 134. Said element 135 has flanges 136 and 137 arranged respectively on opposite sides of the guide 130 to permit restricted free movement of the element 135. By gravity the flange 136 of element 135 bears against the guide 130 in which case its pushing ledge 138 is in the same plane as the flange 121 of the coupling lever 117. The guide 130 has a slot 139 through which the axle 123 passes, said slot being so arranged as to enable the guide 130 to carry out all necessary movements. These movements of the guide 130 and thus that of the pushing edge 138 are composed of two movements as may be gathered from the foregoing. The first movement is a swinging movement of the guide 130 about the pivot 132' of the lever 132. This is produced by the lever 124 turned by the pin 127 about the shaft 123 by means of the pin 128 engaging with the slot 129 of the guide 130 swinging the latter about the pivot 132'. This swinging takes place with every actuation of the machine crank or of the shaft of the main machine and with the aid of it the pushing edge 138 is every time brought into the path of the flange 121 of the coupling lever 117. The second movement of the guide 130 consists of a raising and lowering corresponding to the raising and lowering of the counting mechanism. This is effected by swinging out the double lever 132 about the pin 131 by means of the arm 133 whereby the guide 130 hinged to the double lever by means of the pin 132' is raised and lowered.

In case of a current printing of the items or intermediate sums the raising of the counting mechanism is effected in such a manner that only towards the end of the return movement of the machine crank is the counting mechanism lifted from the toothed wheel gearing of the adjusting mechanism; consequently in case of a current printing of the items and intermediate sums the raising of the guide 130 does not take place until at the end of the return movement of the machine crank, that is to say in a position in which the pushing rod 75 together with its pin 117 has been again raised (Figs. 2 and 2^a). Hence the lower arm of the lever 124 can swing out again to the left under the action of the spring 125 and thereby swing the guide 130 with the pushing edge 138 of its top piece 135 out of the path of the stop flange 121 so that upon a raising of the guide 130 corresponding to the raising of the counting mechanism in case of a current printing of items and intermediate sums the pushing edge 138 does not actuate the coupling lever 117.

When printing total sums however the rising of the counting mechanism as is well known takes place at the commencement of the return movement of the crank, that is to say at an instant, in which the pushing rod 75 and the element 117 thereof controlled by the machine crank are still in a lowered position, that is to say in the position corresponding to that of Fig. 1. If at this moment the guide 130 is raised by the double lever 132, the striking edge 138 of its top piece 135 is beneath the stop flange 121 of the coupling lever 117, and hence when being raised will strike against flange 121 and thereby bring the coupling lever 117 into the position shown in Fig. 1, in consequence of which upon the next following first printing of item of a new calculation it is forced to follow the movement of pin 84 of the hammer mechanism for the unit places so that in this case the releasing of the hammer gearing for the sign takes place.

The top piece 135 mounted on the guide 130 serves the object to enable the downward movement of the guide 130 during the current printing of items or intermediate sums, that is to say in the position of the coupling lever 117 corresponding to Fig. 2. During this downward movement the top piece strikes against the flange 121 and can then turn to the side about the pin 134, whereupon after the passing of the flange it returns to its initial position either by its own weight or by the action of the spring.

The device acts in the following manner: The raising of the counting mechanism and the pushing upward of the pushing edge 138 combined therewith occurs simultane-

ously with the printing of the items and of the intermediate sums during the last quarter of the return movement of the hand lever. At this period the pin 127 owing to 5 the machine crank controlling it is already at such a height (at the return movement of the crank the pushing rod 75 lifts itself up) that the pushing edge 138 is no longer underneath the flange 121. Hence the hammer for 10 the mark is not released when the next item is printed. After the printing of the total sums however the counting mechanism is raised already during the first quarter of the return movement of the crank. At this period, however, the pin 127 is still in such a 15 low position that the pushing edge 138 is still in the effective position and upon its upward movement forces the flange 121 to follow its movement, thereby bringing the raised part of the edge 122 into the path of 20 the pin 84 at the unit place of the hammer mechanism. Upon the printing of the next item the pin 84 is swung out to the left and thereby disengages the locking device for the 25 hammer of the sign whereby the printing of the clearing sign is effected. The returning of the lever 117 into its ineffective position takes place at the instant when the hammer of the sign 51 shoots forward by 30 the extension 119 of the hammer pressing the end 118 of the lever 117 to the right.

I claim as my invention:

In clearing sign hammer mechanism for calculating machines the combination of a 35 hammer, a hammer actuating device for the

clearing sign, releasing mechanism for said hammer comprising a lever mounted for sliding and pivotal movement and provided with a notch, a lever revoluble with an element of the hammer actuating mechanism 40 and engageable in said notch, a catch lever mounted for pivotal movement engageable with the hammer and connected to said first named lever, springs to actuate said hammer, catch lever and first named lever, a 45 coupling lever pivotally mounted on the first named lever and arranged for limited pivotal movement, and having a projection, said hammer having an extension arranged in the path of said projection, an oscillatory 50 mechanism arranged for operation with the calculating machine crank and with the counter mechanism thereof and including a lever oscillatable about a fixed axis, a guide link arranged for limited movement with respect to said fixed axis, and an element pivotally mounted on said guide link arranged for limited pivotal movement with respect thereto and connected to said lever 55 for movement by the latter into and out of engagement with said coupling lever.

In testimony whereof I have signed my name to this specification in the presence of two subscribing witnesses.
